UNITED STATES PATENT OFFICE

108,330

DESIGN FOR A LIPSTICK HOLDER

Martine Kane, New York, N. Y., assignor to Helena Rubinstein, Inc., a corporation of New York

Application June 18, 1937, Serial No. 69,899

Term of patent 7 years

To all whom it may concern:

Be it known that I, Martine Kane, a citizen of the United States of America, and residing in New York, New York, have invented a new, original, and ornamental Design for a Lipstick Holder, of which the following is a specification, reference being had to the accompanying drawing, forming part thereof.

The figure is a perspective view of a lipstick holder, showing my new design.

I claim:—

The ornamental design for a lipstick holder, as shown.

MARTINE KANE.
